STEAM EXPANSION CHAMBER

John B. Prather, Hastings on Hudson, N.Y., assignor to Gibbs & Hill, Inc., New York, N.Y., a corporation of New Jersey

Filed Aug. 16, 1961, Ser. No. 131,932
6 Claims. (Cl. 261—115)

This invention relates to an apparatus for the expansion of gases and more particularly to an apparatus for controlling the expansion of relatively large volumes of steam and especially to a chamber for dumping steam from a by-pass for a turbine into the exhaust for the turbine.

In the steam-electric industry it has become increasingly common practice, and in many cycles imperative, to furnish a means for by-passing steam around the turbine. Such steam is normally dumped into the turbine exhaust system. Even where by-passing steam is not essential, a by-pass adds greatly to the flexibility of operation of steam operated turbines. Thus by-pass systems serve a number of functions depending upon the type of power unit in which they are installed. In general, however, they may be classified under one of the following categories:

(a) By-pass to match steam and metal temperatures in a conventional fossil fuel cycle. This serves to avoid excessive thermal shock in the turbine at start-up.

(b) By-pass for start-up and trip-out when a once-through type boiler is used. By this means water and steam are recycled until proper steam flow and steam temperature are established prior to starting and loading the turbine generator.

(c) By-pass for start-up and trip-out in a nuclear fuel cycle. In some nuclear power plants a by-pass may be required for starting a secondary steam cycle. This also provides a means for conserving valuable condensate when the electrical load is dumped and the residual reactor heat must be dissipated.

Although different purposes are served by each of the by-pass arrangements mentioned above, certain design criteria are common to all for, in each case, provision must be made for cooling and throttling a considerable quantity of superheated steam which is then dumped into the exhaust system for the turbine. Considerable data is available, and considerable work has been done, on throttling and cooling the by-pass steam before it reaches the exhaust for the turbine. For example, throttling is accomplished by expansion through reducing valves, piping, and a series of orifices of increasing area and water sprays are used to cool the steam. Yet important unsolved problems are involved in dumping the steam from the by-pass conduit at several atmospheres, or as high as 100-150 p.s.i., and often at temperatures in excess of 175° F. which is the maximum temperature normally accepted by the industry. As stated the steam is normally dumped into the exhaust for the turbine, or into the main condenser, operating at a relatively low absolute pressure of a few p.s.i. For instance, systems devised heretofore for dumping steam at several atmospheres, or higher, to relatively low turbine exhaust temperatures and high vacuum have resulted in extreme noise, vibration (in some cases fatigue failure) and serious erosion.

It is an important object of this invention to provide

2

a simple, compact, and low cost gas expansion device which will solve problems last mentioned above and related problems. It is a more specific object of the invention to provide an expansion chamber which will expand large quantities of by-pass steam and control its temperature so that it can be dumped, or exhausted, into the exhaust, or condenser, for the turbine without creating uncomfortable noise levels or damaging vibrations.

Other objects, advantages and features of the invention will be apparent from the more detailed description which follows.

The invention will be described by reference to a particular embodiment of the invention shown in the accompanying drawings.

15 In the drawings:

FIG. 1 is a vertical section of an expansion chamber from which by-pass steam can be dumped to the exhaust line of a turbine;

FIG. 2 is a perspective view of the expansion chamber 20 of FIG. 1; and

FIG. 3 is a flow diagram of a steam by-pass for a power plant utilizing the expansion chamber of FIGS. 1 and 2.

In the various figures the same numbers are used to 25 represent like elements. As shown in FIGS. 1 and 2, the steam enters the dump chamber 11 through a pipe 12 located at the axis of a series of alternately facing and nested semi-cylindrical diaphragms 13, 14, 15, 16 and 17 of progressively larger radii. Pipe 12 is provided 30 with a series of holes 18 in the side facing the innermost diaphragm 13 constituting orifices through which steam can expand into the space between pipe 12 and diaphragm 13. To prevent spillover between cylinders, to provide means for supporting the cylinders and to hold 35 them in spaced relationship, and to provide substantially rectangular nozzles 18, 19, 20, 21 and 22 through which the steam can expand the various cylinders are overlapped by 5 to 10° of arc and provided with supports 27 described in detail below. The steam also expands as it 40 flows through the nozzle 23 formed between diaphragm 17 and the outer walls of the chamber 24. There is a further expansion when the steam flows through the outlet 25 into the exhaust system.

It will be seen from the flow line 26 that following each 45 expansion between each diaphragm and between the outer diaphragm and the wall of the chamber the steam undergoes a path reversal of 180° during which no work is done. The kinetic energy, therefore, is dissipated and the steam is reheated at constant pressure towards its original enthalpy. Thus, on a theoretical basis, the stages of expansion are isenthalpic. The expanding steam follows this pattern from stage to stage until it has reached condenser pressure. Nozzle areas formed by overlapping diaphragms are selected to avoid sonic steam velocities or at least objectionable noise levels.

The semi-cylindrical diaphragms are supported and held in spaced relation by lateral supports 27 and by longitudinal support 28. The supports 27 are positioned to interfere as little as possible with the flow of steam 60 while the support 28 serves the dual function of forming a partition, or dam, in the space between adjacent nested diaphragms whereby whirling of the steam is minimized and an even distribution of the steam is facilitated.

In order to control the enthalpy of the steam, water

is brought into a low pressure area of the expansion chamber through conduit 29 and branch conduit 30 and injected into the steam in the low pressure area through nozzles 31 where it flashes into steam. In order to realize a temperature of not more than 175° F., it is seen that the water should be introduced into a low pressure region of the expansion chamber at which the pressure is that of saturated steam at 175° F. Necessarily this is an outer region which facilitates maintenance of the equipment.

The walls 24 of the chamber 11 are protected against erosion by the steam at relatively high pressure by an internal shell 32 of an erosion resisting material such as stainless steel.

It will be seen that this expansion chamber is simple in design, is easy to maintain, and can be economically constructed. For example, it can be made by assembling common rolled and flat sections of steel plate and then welding them at their points of contact. The combination of low cost material and simplicity of design makes it possible to provide the expansion chambers at very reasonable costs.

The expansion chamber (actually two were used) has proven fully satisfactory in use in a by-pass for a 150 mw. turbine in a steam-electric power plant using a once-through boiler. The steam-electric unit was designed to operate at 2400 p.s.i.g. and 1000° F. with reheat to 1000° F. This system is shown diagrammatically in FIG. 3. As shown in FIG. 3, steam from the superheater is expanded through valve 40 and is mixed with water spray at 41, after which, it enters separator 42. The steam then flows through re heater 43 serving to protect the re heater against excessive temperatures. Thereafter the steam flows through conduit 44 to spillover valve 45, which is adjusted so as to limit the downstream pressure, namely, that entering the expansion chamber 11 to 100 p.s.i. Reduction in the enthalpy of the steam is accomplished in the mixing chamber 46 located between the spillover valve and the dump chamber. In the expansion chamber 11, the temperature is further reduced in the manner described before by the addition of a water spray at a point in the expansion chamber where the pressure has been reduced to that of saturated steam at 160° F. In this way, the steam can be dumped into the exhaust of the turbine at a temperature below the required 175° F. and at a pressure which will not cause excessive vibration and sonic disturbances even though the pressure in the exhaust does not exceed several pounds or even 1.5 inches mercury absolute, i.e., 28.5 inches vacuum.

In the actual operation of the steam-electric power plant two expansion chambers 11, as shown in FIGS. 1 and 2, were located on the flat but sloping sides of the condenser neck 47. These dump chambers were approximately 85" wide, 60" high, and 58" long. They were made of carbon steel plates formed and welded as described above.

It is obvious the gas expansion chamber of this invention is extremely versatile in use and is not limited to use in the steam by-pass cycle of a power plant. For instance, it will find wide usage for the expansion of gases and the reduction of temperature in the petroleum industry. It is apparent the number of diaphragms can be increased at will and that a series of orifices of increasing area can be provided so that the velocities therethrough are at, or below, sonic velocities while, at the same time, dissipating the kinetic energy of the gases between expansions.

It will be obvious, for reasons given above, that certain advantages inherently reside in the use of semi-cylinders or substantially semi-cylinders, as baffles. It is apparent, however, that the principles of the invention can be practiced with any type of trough-like alternately facing and nesting overlapping elongated diaphragms and the expression "substantially semicylindrical" contemplates such devices.

Although the invention has been described with reference to the structural details of a particular embodiment illustrated in the drawings, it is to be appreciated that the invention is not to be considered to be limited to all of the details thereof. The invention contemplates various combinations of structural features of the illustrative embodiment within the spirit of the invention and the scope of the invention as defined in the appended claims.

What is claimed is:

1. A gas expansion chamber comprising: first, second and third diaphragms each having opposite ends, opposite edges, and a concave surface, the concave surface of said first diaphragm facing the concave surface of said second diaphragm with the edges of said second diaphragm straddling said first diaphragm and overlapping and spaced a first distance from the edges of said first diaphragm, the concave surface of said third diaphragm facing the concave surface of said second diaphragm with the edges of said third diaphragm straddling said second diaphragm and overlapping and spaced a second distance from the edges of said second diaphragm, said second distance being greater than said first distance, first wall-forming means closing one end of said first diaphragm and the corresponding ends of said second and third diaphragms except for an aperture located in said wall-forming means between said first and second diaphragms, second wall-forming means closing the ends of said first, second and third diaphragms opposite the ends closed by said first wall-forming means, first nozzle-forming wall means extending between and attached between one pair of overlapped edges of said first and second diaphragms, second nozzle-forming wall means extending between and attached between one pair of overlapped edges of said second and third diaphragms, one of said edges of each of said pairs of edges being the same edge, said first and second nozzle-forming wall means assisting in conjunction with said pairs of edges and said first and second wall-forming means in channeling gas flow as well as supporting said first, second and third diaphragms relative to one another and permitting desired gas expansion.

2. The combination of claim 1 including a gas inlet pipe extending through said aperture and terminating between said first and second diaphragms, the portion of said pipe between said first and second diaphragms including at least one aperture facing said first diaphragm.

3. The combination of claim 2 including first partition means extending between said pipe and said first diaphragm and second partition means extending between said pipe and said second diaphragm, said first and second partition means being located substantially perpendicular to said first nozzle-forming wall means and assisting in providing mutual support for said pipe and said first and second diaphragms.

4. The combination of claim 3 including additional diaphragms, each of said additional diaphragms having a concave surface which faces and at least partially surrounds said first, second and third diaphragms, and means for introducing a fluid other than said gas between at least two of said diaphragms.

5. The combination of claim 1 including a gas inlet pipe extending through said aperture and terminating between said first and second diaphragms in a closed end, the portion of said pipe between said first and second diaphragms including a plurality of apertures opening toward said first diaphragm.

6. The combination of claim 5 including first partition means extending between said pipe and said first diaphragm, second partition means extending between said pipe and said second diaphragm, and third partition means extending between said first and third diaphragms, said first, second and third partition means lying substantially perpendicular to said first and second nozzle-forming wall means, certain of said plurality of apertures lying on opposite sides of said first partition means, whereby said

partition means provide mutual support for said pipe and said first, second and third diaphragms and further provide two flow paths for gas emitted from said pipe.
